ROTARY DRAG BIT

Joseph J. Whalen, Oklahoma City, Okla.

Application March 8, 1937, Serial No. 129,603

6 Claims. (Cl. 255—61)

This invention relates to a drill bit and more particularly to such a bit employed in the drilling of deep wells by the rotary method. It has been called a drag bit since it is not provided with 6 roller cone cutters but with a chain type cutter having large plurality of teeth which are adapted to scrape and saw the formation as the bit body rotates.

When any one of several known particularly 10 hard underground formations are encountered in the drilling of a well, few bits of present design can cut more than from two to ten feet into the formation before they become so dull as to be almost completely ineffective, even in softer formations. This necessitates the removal of the entire string of drill pipe and the replacing of the 15 worn bit. When drilling at a depth of 4,000 feet, the replacing of a worn bit takes from five to nine hours in time, and in addition results in considerable wear and tear on the drilling machinery, 20 and thus shortens its life.

It is the chief object of my invention, therefore, to provide a bit the teeth of which, after they become worn, may be moved to an inoperative position and be replaced by new cutting teeth without the necessity of withdrawing the bit from the hole. This elimination of the necessity of frequently 25 withdrawing the bit from the hole results in a large saving of time as well as the saving of much 30 wear and tear on the drilling equipment.

Other objects of the invention are: to provide a bit having a large plurality of cutting teeth, only a comparatively small number of which perform the cutting function at any one time, and 35 which small number may be moved out of cutting position at will and replaced by other teeth in the group, without removal of the bit from the hole; to provide a bit of the drag tooth type which presents so very large a number of teeth to the formation 40 being cut that very little downward pressure on the bit is required, and consequently the hole is drilled much straighter than by bits of present design; to provide a bit which is capable of entering the drill hole, after having been withdrawn, without the necessity of previously reaming the hole, thus saving considerable time which would otherwise be spent in reaming the hole, as 45 well as saving considerable wear and tear on the drilling machinery; to provide a bit, the moving parts of which will last indefinitely, because they are held stationary during the rotation of the bit in the hole; and which because of all the above 50 features is more efficient in drilling wells than bits heretofore available to the oil trade.

55 Other objects of the invention will be seen from

a consideration of the following detailed description when read in connection with the accompanying drawings which form a part of this application.

Referring to the drawings:

Figure 1 is a side perspective view of the bit in drilling position within a hole;

Figure 2 is a perspective view of one of the toothed links of which the endless chain is composed;

Figure 3 is a plan view of a portion of the endless chain showing the manner in which the toothed links fit together to form the chain;

Figure 4 is a side sectional view of the upper portion of the bit showing particularly the construction of the fluid operated means for moving the endless chain, and for locking it against movement;

Figure 5 is a sectional view of the same portion of the bit as shown in Fig. 4, but is taken at right angles to the Fig. 4 view, along the line 5—5 of Fig. 1;

Figure 6 is a sectional view taken along the line 6—6 of Fig. 5 and shows more clearly the relation of the chain and its driving sprockets;

Figure 7 is a sectional view taken along the line 7—7 of Fig. 4 showing particularly the manner in which the four longitudinal circulation passages converge into two passages;

Figure 8 is a sectional view taken along the line 8—8 of Fig. 4 and shows the upper chain pulley together with the guide flanges at the outer edge of the chain way;

Figure 9 is a side perspective view of the lower end of the bit showing the absence of teeth on some of the chain links as a means for allowing the bit to re-enter the hole without the necessity for reaming the hole;

Figure 10 is a perspective view of the same portion of the bit shown in Fig. 9, but is taken at right angles to the Fig. 9 view;

Figure 11 is a sectional view taken along the line 11—11 of Fig. 13 and shows particularly the shape of the chain way;

Figure 12 is a sectional view taken along the line 12—12 of Fig. 10 and shows the lower chain pulley and the flanges for guiding the chain along its way;

Figure 13 is a sectional view of the lower portion of the bit taken along the line 13—13 of Fig. 9 and shows particularly the manner of mounting the lower chain pulley and the bit head on the bit body; and,

Like characters of reference designate like parts in all the figures.

Generally, my improved bit comprises an elongated bit body, an endless chain with cutting teeth on its links, a pair of pulleys over which the chain moves, longitudinal guide ways formed in the sides of the bit body for guiding the chain over the pulleys, a pair of sprockets for moving the chain over the pulleys when desired, and 10 for locking the chain against movement when desired; and fluid pressure means for moving and controlling the movement of the sprockets.

The bit body 20 is an elongated substantially cylindrical member but has longitudinal water courses 21, 22, 23, and 24 (Figs. 1 and 7) extending substantially throughout its length, formed on its outer surface. It is also provided interiorly with four longitudinally extending fluid circulation courses 25, 26, 27 and 28 which extend from 15 its upper threaded end 29 to a point 30 intermediate its ends, where they converge with two larger courses 31 and 32 by means of short cross ducts 33, 34, 35 and 36, the outer ends of which are plugged, as shown in Fig. 7. These two courses 25 31 and 32 extend longitudinally downward in the bit body from this point to the lower end of the bit (Fig. 13) where they communicate with hollow bolts 37 and 38 which serve to rigidly position a bit head 39 on the lower end of the bit body. 30

In addition to the above the bit body 20 is also provided with a pair of oppositely positioned longitudinally extending chain ways 40 and 41, a cross sectional view of which, without the chain 42 is shown in Fig. 8, and with the chain in Figs. 35 7 and 11, and in which the chain moves and is guided.

Near its upper end the bit body 20 is provided with a pair of perpendicularly intersecting longitudinally extending slots 43 and 44, the offices of 40 which will be hereinafter explained.

The lower portion of the slot 43 houses an upper chain pulley 45 (Figs. 4, 5 and 8) which is journaled on a spindle bolt 46 (Fig. 5), the inner end of which is threaded into the bit stock, and 45 the outer end of which is hollowed as at 47 (see also Fig. 1) to receive a key (not shown) of similar shape for removing the spindle from its seat.

A lower chain pulley 48 (Fig. 13) is rotatably mounted between the spaced lower ends of the 50 bit head 39 on a spindle 49 which is held in position by having its ends welded to the head, or by any other suitable means. Figs. 11 and 13 clearly show the cross sectional shape of the upper end of the bit head, which tightly fits into a suitably 55 sized socket in the lower end of the body 20. The entire head is rigidly held in its socket in the lower end of the body 20 by means of the hollow bolts 37 and 38 which are screwed into the lower end of the bit body, and the bores of which communicate with the circulation courses 31 and 32, as previously explained.

Both the upper and lower pulleys are in alignment with each other and with the chain ways 40 and 41, so that the chain 42 is guided directly 60 over both pulleys, when it is moved. Figs. 10 and 12 show a chain way identical in cross section to the chain ways 40 and 41 formed around the outer edge of the head 39.

The endless chain 42 is composed of a plurality of links 50, one of which is shown in Fig. 2, and all of which are provided on one side with substantially V-shaped lugs 51. The inner edge of each link is arcuate to substantially conform to the edges of the pulleys 45 and 48, this relation being shown clearly in Fig. 12. The outer

edges of the links form a plurality of teeth 52. The various links are identical in shape. The teeth are of the same size, number and spacing on each link but are so located between the ends of the links that when the flat sides of two of the links are placed together the points of the teeth on one of the links align with the valleys between the teeth on the other link, as clearly shown in Figs. 6 and 9. This arrangement presents a great many more cutting teeth to the 10 formation being drilled than if the points of the teeth aligned.

The cutting chain 42 is four links wide, the two center links being positioned with their flat sides together, and the two connecting outer links being positioned with their lugged sides together, as 15 shown in Fig. 3. Removable pins 53 are used to fasten the adjacent ends of the links together, and these pins are of a length slightly less than the width of the chain ways 40 and 41 at their 20 widest points (see Fig. 8), the sides of the ways thus preventing loss of the pins 53. A suitable number of adjacent "blank" links are provided at some point in the chain, as shown in Fig. 12. With the chain in the position shown in this 25 figure, it will easily be seen that the absence of teeth on these blank links sufficiently narrows the over-all size of the lower end of the bit to permit it to re-enter a hole after being withdrawn without the necessity of first reaming the hole. 30

The mounting of the chain on the bit having been described, I will now describe one means for controlling the movement of the chain over its pulleys. Referring to Figs. 4, 5 and 6, I provide a pair of identical spaced sprockets 54 and 55, which are concentrically journaled within the slot 43 on a pin 56, so that they straddle the chain 42, and so that their adjacent teeth straddle the opposite protruding ends of the chain pins 53, as clearly shown in Fig. 6. The teeth on these 40 two sprockets are so spaced that they contact each pin 53 as the chain moves over its pulleys. A second pair of gears 57 and 58 are spaced apart in exact alignment with the sprockets 54 and 55, and are concentrically keyed on a spindle 59, 45 which in turn is journaled in the body walls. Between the two gears and also keyed to the spindle 59 by means of a key 60 (Fig. 4) is a ratchet wheel 61. On their adjacent inner surfaces each 50 of the gears 57 and 58 are provided with an inwardly extending circular hub (62 and 63 respectively) which hubs serve to journal the spaced yokes 64 and 65 of a crank arm 66, to the outer end of which is pivotally connected one end of an operating link 67 which serves to rotate the crank 55 arm 66 about its axis. Intermediate its ends and between its spaced sides the crank arm 66 pivotally carries a pawl 68, which is in alignment with the ratchet wheel 61, and is adapted to contact the teeth of the ratchet wheel by gravity. 60

With this arrangement it may easily be seen by one skilled in the art that when the operating link 67 is forced downward the crank arm 66 is forced to rotate on the hubs 62 and 63 (its axis) and as it rotates the pawl 68 will contact 65 the teeth of the ratchet wheel 61 forcing the ratchet wheel to rotate. In rotating, the ratchet wheel 61 rotates its shaft 59 which in turn forces the rotation of the spaced gears 57 and 58, which in turn rotate the sprockets 54 and 55, which 70 move the chain 42 over its pulleys.

The interrelation of the gears 57 and 58 and the sprockets 54 and 55 will now be more fully described. As previously stated, the gears 57 and 58 are respectively in vertical alignment with 75

the sprockets 54 and 55 and their respective axes are so spaced apart that the respective teeth of the gears and sprockets are in mesh. The gears 57 and 58 have fewer teeth than the sprockets 54 and 55 and between adjacent teeth the gears are provided with arcuate blanks, all of which are designated by the numeral 69.

In rotating, as one of the teeth on the gears leaves the valley between two adjacent teeth on the sprockets, the edge of the following arcuate blank contacts only the tip of the next sprocket tooth, and by the time it forces the tooth a very short distance (to the position shown in Fig. 4) the edge of the blank 69 leaves the tip of the tooth. Further rotation of the gear, which incidentally requires very little power, causes the blank 69 to slide over the tips of the adjacent sprocket teeth to the position shown in Fig. 4, at which point further rotation of the gears is interrupted by means which will be hereinafter described. When in this position the gears 57 and 58 are held against accidental movement in either direction preferably by leaf springs 70 and 71, and 72 and 73 respectively (Figs. 4 and 6). The springs 70 and 72 are identical, as are the springs 71 and 73, and their curved ends maintain a constant pressure against opposite edges of the gears 57 and 58. Thus, after the gears have been moved to the locked position shown in Fig. 4, the crank arm 66 and its pawl 68 are free to return to their normal positions without the possibility of the gears 57 and 58 also being rotated. In this position the gears 57 and 58 positively lock the sprockets 54 and 55, against rotation, and the chain 42 is thus held against movement about its pulleys. The springs 70 and 72 are both mounted on the inner surface of a plate 74 which is preferably welded to the bit body 20, closing one end of the slot 43, from its upper end to a point adjacent the location of the sprockets 54 and 55. Likewise the other end of the slot 43 is closed by a plate 75, which carries the springs 71 and 73 on its inner surface. These plates, however, are not placed in position until after all of the above described means for controlling the movement of the chain has been assembled within the slot 43.

The fluid pressure power means for operating the above described chain controlling mechanism will now be described. To the upper threaded end 29 of the body 20 is connected a cylinder barrel 76, the lower portion 77 of which is substantially the same in outside diameter as the body 20. The upper portion 78 is reduced in diameter and its upper end is formed for connection to the drill pipe 79. The bore 80 of the lower portion 77 is considerably larger than the bore 81 of the upper portion. Within the lower portion 77 is a cylindrical sleeve 82, the outer wall of which is spaced from the wall of the portion 77, leaving an annular space therebetween. This sleeve 82 is integral with the lower end of the portion 78, the two together forming a cylinder. At the upper end of the sleeve 82 is provided a plurality of ports 83 and 84, which afford communication between the cylinder and the annular space between the sleeve and the portion 77. Intermediate its ends the upper portion 78 is provided with an internal annular shoulder 85, which serves to limit the penetration of the drill pipe 79 into its upper end, as well as to limit the upward movement of a piston 86 in the cylinder.

The piston 86 has a small bore 87 through its upper end with a valve seat 88 formed at the

inner end of this bore. The interior bore of the piston is abruptly enlarged at this point to form a cage for a valve 89. The lower end of the valve 89 is of a diameter to permit it to easily slide longitudinally within the enlarged bore of the piston. The integral valve head 90 is of a smaller diameter and is shaped to fit the seat 88. A plurality of longitudinal ports 91 and 92 afford communication between the space within the piston above the valve 89 and the space below the valve 89. The valve 89 has a central threaded bore by means of which the upper end of the piston rod 93 is connected to the valve, and indirectly to the piston. The lower end of the piston 86 is threaded internally to receive an annular ring 94, which serves to limit the movement of the valve 89 within the piston, yet which permits free flow of fluid through the lower end of the piston when the valve is open.

The upper end of the body 20 is centrally bored to form a guide for the piston rod 93, the lower end of which extends into the slot 43 where it is connected pivotally to the upper end of the operating arm 67. This central bore is enlarged in its upper portion to accommodate a usual packing gland 95 and packing gland nut 96 which serve to prevent leakage of fluid past the rod as it reciprocates. A coil spring 97 surrounds the piston rod 93 within the cylinder barrel 76. Its upper end bears on the lower end of the piston and its lower end bears on the upper end of the body 20, and it serves to normally hold the piston at the upper end of its stroke. When the piston is at the upper end of its stroke the valve within the piston is necessarily open because the connection 98, which is threadedly secured to the lower end of the piston rod 93, limits the upward movement of the rod 93, by contact with the top wall of the slot 43, and consequently the upward movement of the valve 89 which is attached to its upper end.

This connection 98 is of a size to easily slide within the slot 43 as the rod reciprocates, as is clearly shown in Fig. 5. It carries a guide pin 99, the ends of which protrude from either side of the connection 98. These protruding ends travel in the slot 44 the sides of which thus guide the lower end of the piston rod 93 in its travel. The pin 99 also serves to pivotally connect the upper end of the operating arm 67 in the bifurcated lower end of the connection 98. After the pin 99 has been inserted into the connection 98, and keyed in position by a cotter pin 100, the slot 44 is sealed at each end by plates 101 and 102 (Figs. 1 and 5) which may be welded or otherwise secured to the outer surface of the body 20.

Operation

In operation the bit is secured to the lower end of the drill pipe in the usual manner, the blank links of its chain 42 being in the position shown in Fig. 12. The bit is then lowered to the bottom of the well. During its downward travel it is understood that the sprockets 54 and 55, the arm 66, the gears 57 and 58, the piston 86, and its valve 89, are in their normal inoperative positions, as in Fig. 4; and the chain is thus locked against movement over its pulleys. The valve 89, being open, permits circulation of fluid through the circulation courses 31, 32, 25, 26, 27 and 28, through the ports 91 and 92, through bore 87 and into the drill pipe 79.

When the lower end of the bit reaches the bottom of the well, fluid pressure is applied through the drill pipe 79. The fluid passes through the

bore 87, and since neither this bore 87 nor the ports 91 and 92 afford a sufficiently large outlet passage area to accommodate the full volume of fluid, a pressure is created above the piston 86, 5 forcing it downward in its cylinder, against the tension of the spring 97. When the piston has moved a short distance downward, the valve 89 is closed, shutting off fluid circulation and placing the full pump fluid pressure on the piston. 10 As the piston travels downward, the lower end of its rod 93 forces the operating link 67 downward, which in turn moves the crank arm 66 toward the position shown in Fig. 6, and thence to the position shown by the dotted lines of Fig. 4. The 15 side pull on the lower end of the piston rod 93 is relieved by the pin 99 sliding vertically in its guide slot 44. As the crank arm 66 rotates, it moves the gears 57 and 58 as previously explained. The blanks 69 are moved away from their locking 20 contact with the adjacent teeth of the sprockets 54 and 55, and one of the long teeth on each gear then contacts the teeth on the sprocket. As the sprockets 54 and 55 are rotated they move the chain 42 over its pulleys. After the long tooth 25 on each of the gears 57 and 58 leaves the respectively adjacent teeth on the sprockets, the next arcuate blank 69 on the gears slides into locking contact with the sprocket teeth, and the chain is again locked against movement. The linkage of 30 the piston with the gears 57 and 58 is such that as the gears 57 and 58 again reach their normal positions, as in Fig. 4, with the crank arm still in the position shown by the dotted lines, the piston reaches the lower end of its stroke, and its upper 35 end passes the ports 83 and 84, opening them completely, and permitting the fluid to pass downward through the annular space between the sleeve 82 and the lower portion of the barrel 76, through the circulation courses 25, 26, 27, 28, 31 and 32, and out the lower end of the bit through 40 the hollow bolts 37 and 38. The downward stroke of the piston is limited by the contact of the pin 99 with the bottom of the slot 44. The excess pressure in the drill pipe 79 is easily sufficient to move the piston to the extreme lower end of 45 its stroke, even after the ports 83 and 84 start to open, especially since the only work being performed by the piston at this point in its travel is the sliding of the blanks 69 into locked position. 50 Friction, together with the tension of the spring 97 against the further downward movement of the piston, is also easily overcome by this excess pressure, so that the ports 83 and 84 will remain fully open so long as normal pump pressure is 55 maintained. So long as the fluid pressure in the drill pipe is maintained the piston will remain at the lower end of its stroke, and consequently the link 67 and the crank arm 66 will remain in the position shown by the dotted lines in Fig. 4. 60 The drilling proceeds with the various parts in this position, and with the chain locked against movement, as shown.

When the fluid pressure is released, however, the crank arm 66 and its link 67 return to the 65 position shown by the solid lines in Fig. 4, and the next time fluid pressure is applied the complete cycle of movement, as just described, is repeated. The ratio of gearing between the ratchet 61, the gears 57 and 58, and the sprockets 54 and 70 55 is such that the chain moves a distance equivalent to the length of one link each time the crank arm moves from the position shown in solid lines (Fig. 4) to the position shown in dotted lines.

In ordinary drilling, this movement would bring 75 a sufficient number of new teeth into contact with

the formation. If desired to move the chain a greater distance over its pulleys, and thus bring, for instance, two complete new links of the chain into cutting position, it is only necessary to stop the fluid pressure and again apply it. 5

With further regard to the valve 89, it will also be noted that when the pump pressure is removed, the piston is returned to the upper end of its stroke by the action of the spring 97, and that as it returns, the valve 89 opens. If it is 10 desired to withdraw the bit from the hole, therefore, the fluid in the drill pipe is free to drain through the piston valve and out through the circulation courses, as previously described. Sections of the drill pipe may thus be removed 15 "dry" at the earth's surface.

It is believed that the manner of assembling of the various parts will be entirely clear to one skilled in the art after having read the above description in connection with the accompanying 20 drawings. It is therefore considered sufficient to say only that when it is desired to replace the chain 42, the spindle 46 is unscrewed and removed from the bit. Its removal permits the upper pulley 45 to drop to the bottom of the slot 25 43. The uppermost chain links are then free to drop downward in the slot 43 so that the pins 53, in any one of the links, may be easily aligned with a hole 103 in the bit body, in which position the pin may be easily removed from the 30 chain, and the chain separated. The chain may then be easily removed through the lower end of the slot 43 (Fig. 6).

While I have described and illustrated a specific embodiment of my invention, I am aware 35 that it is capable of modification, and I do not wish to be limited except by the prior art and the scope of the appended claims.

I claim:

1. A device of the class described comprising: 40 an elongated bit body; a pair of pulleys rotatably mounted on said body; a cutter composed of a plurality of links fastened together to form an endless chain, each link having a plurality of cutting teeth thereon; said cutter adapted to 45 be moved over said pulleys; ratchet operated gear and sprocket means for moving said cutter over said pulleys and also for locking it against movement over said pulleys; and power means carried by the body for operating and controlling said 50 last mentioned means.

2. A device of the class described comprising: 55 an elongated bit body; a pair of pulleys rotatably mounted on said body; a cutter composed of a plurality of links fastened together to form an endless chain, each link having a plurality of cutting teeth thereon; said cutter adapted to be moved over said pulleys; ratchet operated gear and sprocket means for moving said cutter over said pulleys and also for locking it against movement over said pulleys; and fluid pressure power means for operating and controlling said last mentioned means.

3. A device of the class described comprising: 65 an elongated bit body having a plurality of longitudinally extending internal fluid passages therethrough; a cutter pulley rotatably mounted in a through slot in said bit body intermediate its ends; a bit head rigidly secured to the lower end of said bit body; a cutter pulley rotatably 70 mounted in said bit head; an endless chain type cutter mounted to move over said pulleys; and means for moving said cutter over its pulleys and also for preventing its movement over said pulleys.

4. A device of the class described comprising: an elongated bit body having a plurality of longitudinally extending internal fluid passages therethrough; a cutter pulley rotatably mounted in a through slot in said bit body intermediate its ends; a bit head rigidly secured to the lower end of said bit body; a cutter pulley rotatably mounted in said bit head; an endless chain type cutter mounted to move over said pulleys; means for moving and controlling the movement of said cutter over its pulleys; and fluid pressure means for operating said last mentioned means.
5. A device of the class described comprising: an elongated bit body having a plurality of longitudinally extending internal fluid passages therethrough; a cylinder barrel secured to the upper end of said bit body, its bore in communication with said fluid passages; a cutter pulley rotatably mounted in a through slot in said bit body intermediate its ends; a bit head rigidly secured to the lower end of said bit body; a cutter pulley rotatably mounted in said bit head; an endless chain type cutter mounted to move over said pulleys; means for moving and controlling the movement of said cutter over its pulleys; a fluid pressure operated piston in said cylinder barrel for operating said last mentioned means; and a valve in said piston for controlling the flow of fluid therethrough and through the fluid passages in said bit body.
6. A device of the class described comprising: an elongated bit body having a plurality of longitudinally extending internal fluid passages therethrough; a cylinder barrel secured to the upper end of said bit body, its bore in communication with said fluid passages; a cutter pulley 10 rotatably mounted in a through slot in said bit body intermediate its ends; a bit head rigidly secured to the lower end of said bit body; a cutter pulley rotatably mounted in said bit head; an endless chain type cutter mounted to move over 15 said pulleys; means for moving and controlling the movement of said cutter over its pulleys; a fluid pressure operated piston in said cylinder barrel for operating said last mentioned means; and a valve in said piston for controlling the 20 flow of fluid therethrough and through the fluid passages in said bit body.

JOSEPH J. WHALEN.
